OIL BURNER AND FUEL FEED SYSTEM
FOR SAMEFrederick Ritchie Husband, Thames, Auckland,
New ZealandApplication February 4, 1948, Serial No. 6,127
In New Zealand December 19, 1946

9 Claims. (Cl. 158—63)

1

The invention relates to oil burners and fuel feed systems for same, wherein liquid fuel is pre-heated and vaporized for passing to a combustion space for the purpose of generating heat.

In known oil burning systems of the kind aforesaid, internal pressure generated at the burner, acts to retard the flow of fuel to the latter, necessitating the employment of means to create a counterpressure, and apply the latter behind the fuel, as for instance, by the introduction of pressure into the fuel tank in order to force the fuel to the burner, so that the latter may function.

The use of special pressure creating means, and the application of same to fuel supply systems of oil burners for the purpose indicated, present disadvantages not readily overcome, and which up to the present have restricted development of the aforesaid class of burner by limiting its application to smaller types of appliances, because as the burners increase in size, the creation of and the application of the counterpressure behind the fuel, becomes a problem of considerable magnitude, until a point is reached when this class of burner can not be economically used.

The primary object of the invention is, therefore, to provide for use with oil burners of the kind referred to, a fuel feed system which avoids or overcomes the disadvantage of the use of special pressure creating and applying means, by utilizing pressure created at the burner, in such a manner that as far as the supply of fuel to the latter is concerned, said pressure cancels itself out, and the fuel is enabled to pass to the burner by gravity, or in other words, there is provided a fuel feed system wherein the fuel, although subjected to pressure, passes to the burner by gravity.

The placing of the fuel under pressure, while it remains gravity operated, enables the pressure generated in the system to be taken advantage of for the purpose of controlling the fuel supply to the burner, and consequently also the heat generated thereby, introducing a safety measure in the operation of the burner.

A special advantage arising out of the dispensing with of the pressure creating and applying means, is the simplification of the construction and the operation of the system, which enables the field of application of the burner to be extended, regardless of the type and size of appliance in connection with which the burner and the improved fuel feed system are used.

2

Other objects of the invention, are to increase the efficiency of the burner by ensuring more complete and effective combustion of the fuel, which gives increased heat with economy in fuel consumption, and cleanliness owing to the elimination of smoke, soot and other residue, and also to provide a simple and fool proof supply system, the operation of which can be controlled by the regulation of the flow of fuel, either manually or automatically, or both, to give increased or decreased heat as required, said system also including a further safety feature provided by a vacuum seal which operates automatically on the fuel supply line, to close same if necessary, and automatic metering of fuel to the burner for priming same.

Briefly, the essential feature of the invention, may be said to consist in providing, through an oil fuel burner of the kind aforesaid, and a source of fuel supply, a circuit whereby pressure generated under heat at the burner, is directed to behind or above the fuel, to provide in said circuit a body of fuel, which is subjected, at opposite sides, to oppositely acting equal pressures, whereby there is created a condition which enables the fuel while under pressure, to pass to the burner by gravity.

Another feature comprised in the invention, is the provision in the burner of an expansion chamber wherein the vaporized fuel is superheated and expanded before being delivered to the combustion area, with the result that reduced air is required to support combustion, and combustion efficiency is increased.

A further feature is the provision of means in the expansion chamber for creating a vacuum seal in the fuel supply tank, and thereby preventing the flow of fuel to the burner in the event of the latter ceasing to function, or should the fuel supply control cock be inadvertently opened, said means also serving to meter fuel to the expansion chamber, when starting up the burner.

Other features include a limiting jet in the fuel supply line as a safeguard against excessive pressure being built up in the system, a heat exchanger for preheating the liquid fuel prior to its passing to the vaporizer, and for cooling gas passed under pressure to the fuel supply tank, and a cooling jet incorporated in the gas pressure line between the burner and the fuel tank.

The above enumerated features, and other features which will become apparent from a study 55 of the following description and accompanying

illustrations, combine to produce the improved oil burner and fuel feed system for same, but it must be clearly understood that the description to be herein given, and the illustrations, are by way of example only, and that the invention is not restricted to the form described and shown, as it will be apparent that the actual apparatus which may be used, will vary considerably in accordance with the type of appliance to which the burner is applied, and the conditions under which the latter operates, the essential features which combine to provide the invention remaining the same in all cases.

For a further understanding of the invention, reference is made to the accompanying drawings, wherein:

Figure 1 illustrates in diagrammatic form, the layout or principle upon which the burner and the fuel feed system for same, operate, while

Figure 2 shows partly in sectional elevation, and partly in elevation, one practical form the invention can take, and,

Figure 3 is a vertical sectional view through the pressure regulator.

Referring to Figure 1 of the drawings, 1 indicates a liquid fuel supply tank, 2 the expansion chamber of a burner, and 3 the jet at which gas burns to heat the chamber 2, gas being supplied to the jet 3 by the tube 6 from the chamber 2; 4a indicates an oil fuel line between the tank 1 and a pressure regulator 16 and 4 indicates a continuation fuel line to a vaporizer tube 5 which opens into the expansion chamber 2, said fuel line 4 having incorporated therein a fuel control cock 7, while 8 is a pressure take off tube leading from the expansion chamber 2 and placed in communication with the top of the fuel tank 1, by a pressure line 9.

With the burner functioning, after having been primed and preheated, and with the control cock 7 open, fuel passes from the tank 1 via the line 4a—4 to the vaporizer tube 5 from which it enters the chamber 2, and is converted into gas and expanded therein to generate pressure, some of the gas under pressure passing to the jet 3, and some passing via the line 9 to the top of the tank 1, to behind or above the fuel therein.

The effect of transferring pressure from the chamber 2 to the tank 1 through the line 9, is to apply behind or above the fuel, that is in the top of the tank 1, a pressure equal to the back pressure which acts in the tube 5 against the flow of fuel in the line 4 to said tube, the result of which is that the fuel is located between two equal pressures which act on the fuel in opposite directions, and so counterbalance or cancel each other out, thereby leaving the fuel free to flow by gravity through the line 4a—4 to the tube 5, to be vaporized therein and passed to the chamber 2 for conversion into gas which is superheated and expanded in said chamber.

By applying equal oppositely acting pressures at opposite sides of the fuel, the latter is put into a state of compression, and advantage can be taken of this condition to provide a convenient method of flame or heat control as will be hereinafter described.

The cycle described will continue to operate as long as fuel is permitted to flow through the line 4 to the vaporizer tube 5.

The foregoing is intended merely to explain the principle or essential feature of the invention, which will now be described in greater detail as embodied in one practical form, suitable

for use in the furnace or firebox of an appliance, such as, for instance, a hot water heater.

As illustrated in Figure 2, there is provided a front plate 11 containing air ports 11a, and adapted to serve as a coverplate to a furnace or firebox, and from which plate 11 there extends a housing 12 adapted for insertion in the furnace or firebox.

The fuel tank 1 is supported by a supporting member 30 a suitable height above the housing 12 to give a desired head of fuel, and so as to be located outside the furnace or firebox when the housing 12 is inserted therein.

The burner comprising the expansion chamber 2 provided with the tubes 5, 6 and 8, and gas nipple jet 3 aforesaid, is located in the housing 12 the required distance from the plate 11, and has surrounding its lower portion an inverted combustion cone 13 positioned to provide between itself and the lower portion of the chamber 2 a combustion area 14.

The combustion cone 13 is open at the top, and also at the bottom, and below it is located a cup or depression 15 in the bottom of the housing 12, to hold liquid fuel used in pre-heating the chamber 2 at the commencement of operations.

The fuel tank 1 is provided with a filler cap 1a, and is a sealed unit when in use, and if desired, it can be provided with means which automatically act to close the tank outlet to the fuel line 4a upon the filler cap 1a being removed, as for instance, when it is necessary to place fuel in the tank 1. This is a safety precaution to prevent flooding of the burner during the filling operation, should the fuel control cock 7 have been left open, said cock comprising a plain needle valve fitted in the fuel line 4 as close as possible to the vaporizer tube 5.

The fuel line 4a leads downwards from the tank 1, and then upwards and to the vaporizer tube 5, a pressure regulator 16 being inserted between the sections 4a and 4 of the fuel line so as to enable the state of compression imposed on the fuel by the oppositely acting pressures, to be utilized for the purpose of providing a method of flame or heat control before referred to.

A heat exchanger 10 provided in the line 9 and through which the fuel line 4 passes, enables heat in the gas passing from the chamber 2 to the tank 1, to transfer to fuel passing from the latter to the vaporizer tube 5, thereby preheating the fuel before it reaches the vaporizer tube 5, and reducing the temperature of the gas under pressure in the line 9 before said gas reaches the tank 1.

As the heated fuel tends to rise, it is essential that the fuel line 4 from the regulator 16 be installed so as to have a continuous slope upwards through the heat exchanger 10 to a point beyond same, in order to facilitate the tendency of the fuel after being heated in the heat exchanger 10, to rise, as if the line 4 was given a downward slope, a condition of turbulence would be created in the line, owing to the heated fuel trying to climb against the flow from the tank 1.

Vaporization commences after the fuel has emerged from the limiting jet 18. The upward slope of the fuel line 4 is to avoid conditions of turbulence in the fuel line due to the effects of the hot fuel climbing back to the tank 1, against the cold fuel coming down. The slope given to the fuel line 4 as it leaves the heat exchanger 10 avoids this condition. Giving the fuel line a downward slope before it enters the heat ex-

changer 10 provides a cold fuel trap, which effectively prevents the hot fuel from flowing back to the tank 1.

The pressure regulator 16 is of conventional design and may comprise a valve 20 adapted to seat upon a valve seat 21 positioned in an axial bore through the body of the regulator, which bore forms a connection between the fuel line 4a from the tank 1 and the fuel line 4 to the burner.

The valve 20, which is spring loaded, is provided with a valve stem 22 having a thrust collar 23 thereon bearing against a flexible diaphragm 24, housed within a diaphragm chamber 25. The diaphragm 24 is adapted to be controlled by a diaphragm loading spring 26 mounted within a sleeve 27 and positioned in the body of the regulator so that the action of this loading spring upon the diaphragm 24 is opposed to the action of the spring loaded valve stem 22 upon the opposite side of the latter. The modulus of the loading spring 26 can be regulated by a knob 10a mounted on a thrust rod 28 and bearing against the loading spring.

The loading spring 26 is adjusted to maintain the valve 20 off the seat 21 to leave the channel through the regulator open, and the modulus of the loading spring 26 is variable by means of the knob 10a on the thrust rod 28, so that the loading can be regulated to withstand only a predetermined pressure arising out of the compression of the fuel between the oppositely acting pressures on the diaphragm 24. Thus, when said predetermined pressure is exceeded the valve 20 closes on its seat 21 and cuts off the supply of fuel from the line 4 through the line 4a to the burner, thereby putting the latter out of action.

In order to prevent the generation of pressures in the system which could be dangerous, precautions are taken to prevent such a condition arising, a limiting jet 18 being inserted in the fuel line 4 at the entrance to the vaporizer tube 5, to restrict fuel delivered to the latter, to an amount sufficient to obtain a desired degree of heat, the orifice of the limiting jet 18 being selected in relation to the orifice of the gas nipple jet 3, so as to provide a variety of flame and pressure conditions, suitable for different uses.

Both the limiting jet 18 and the gas nipple jet 3 are of conventional form.

The pressure line 9 leads from the pressure take off tube 8, which extends into the expansion chamber 2, upwards to the top of the tank 1, the lower portion of the line entering the heat exchanger 10 at the bottom of one end thereof, while the upper portion of said line 9 leaves the opposite end of the heat exchanger 10 from the top thereof.

It is essential that the pressure line 9 be installed with a continuous upward slope to the tank 1, and that the heat exchanger 10 be of such construction, the accumulations of liquid in the line 9 and heat exchanger 10 are avoided, as such accumulations would be responsible for the formation of pressure locks in the line 9, and prevent the full flow of gas to the tank 1, which would result in fuel ceasing to flow through the fuel line 4 to the burner.

As the gas under pressure passing through the line 9 from the expansion chamber 2 to the tank 1, is heated to a high temperature, and as it is undesirable that gas at high temperature should be delivered into the tank 1, means are provided for effecting a reduction in the temperature of the gas prior to its entering the tank 1, and to effect such reduction in temperature, a reducing

jet 17 is provided at the outlet end of the pressure take off tube 8. Furthermore, additional heat is extracted from the gas in the heat exchanger 10, which serves as an expansion chamber for the gas, from which heat is absorbed by conduction into the fuel in the line 4 by the gas coming into contact with the latter where it passes through the heat exchanger 10.

The cooling of the gas by limiting the flow thereof by means of the reducing jet 17, permits a greater degree of expansion of the gas in the pressure line 9, the heat exchanger 10, and the tank 1. The reducing jet 17 has a small bore therethrough and this permits of a certain degree of expansion in line 9, with resultant cooling, this jet also operating to a limited extent as a flow regulator. This latter action results from the condensation factor, due to the radiation effects of the metal exposed to the air in the fuel tank 1 and associated piping 4a-4 from the tank. By limiting the gas flow through the reducing jet 17, due to the very small bore therein, the expansion factor in line 9 is increased, but at the same time the radiation effect resulting in cooling is also more effective. Therefore, as expansion of the gas with resultant cooling is obtained in line 9, due to the small bore of the reducing jet 17, and flow regulation is not required in the sense of actually regulating the flow of the gas, it is the factor of expansion which determines the function of the jet 17 as a reducing jet.

The absorption of heat from the gas in the heat exchanger 10, by fuel in the line 4, not only lowers the temperature of the gas, but also raises the temperature of the fuel, which lowers the viscosity of the latter, rendering it more readily susceptible to vaporization in the tube 5, thereby obtaining the dual effect of maintaining a more uniform rate of gain, together with acceleration in the speed with which working pressures are obtained.

The vaporizer tube 5, and the pressure take off tube 8, are carried downwards in the expansion chamber 2, so that their open inner and lower ends terminate in similar pressure areas, or nearly so, and when starting up the burner, the tube 5 delivers liquid fuel into the expansion chamber 2, which under these circumstances, acts as the vaporizer for starting up purposes.

When, however, sufficient heat is being generated, vaporization of the fuel is effected in the tube 5, and the chamber 2 resumes its proper function of permitting the gas to expand under the action of the heat from the flame in the combustion area 14, and by these means considerable expansion of the gas is obtained before it is projected into the combustion area 14, and as a result, less air is required to support combustion, and increased combustion efficiency is obtained.

Besides providing means for taking of pressure from the expansion chamber 2, for transfer to the tank 1 to be applied behind the fuel therein, the tube 5 enables automatic control of the supply of fuel to the burner to be obtained as follows.

When the fuel control cock 7 is opened to prime the burner, in starting up the latter, air passes into the tank 1 to replace the outgoing fuel, by way of the gas nipple jet 3, tube 6, chamber 2, tube 8 and line 9, so that by carrying the tube 8 well down in the expansion chamber 2, and terminating it at a predetermined distance from the bottom thereof, two important effects can be obtained:

(1) Automatic regulation of the amount of fuel delivered into the chamber 2 for priming purposes, by positioning the lower open end of the tube 8 below the level of fuel required for priming, so that when the fuel reaches said level, it closes the air passage to the tank 1, and sets up a vacuum seal therein, which prevents fuel from flowing from the tank 1 until the seal is broken.

(2) The automatic safety vacuum seal also operates as in (1), in cases where the fuel control cock 7 has been accidentally or otherwise opened, without the burner being started up.

The vacuum seal referred to in (1) and (2), is broken upon the fuel in the chamber 2 being vaporized and converted into gas, when the chamber 2 is heated, the establishing of the seal and the breaking of same being automatic.

The lower end of the gas tube 6 carries the gas nipple jet 3, which is directed towards the expansion chamber 2, the tube 6 being bent to the required angle, and taken through the bottom of the chamber 2, and continued upwards inside the same, so that its upper end is as close to the top thereof as possible, thereby establishing a considerable distance between the open end of tube 6, and the open end of pressure take off tube 8, to provide a satisfactory safety margin in which to establish the vacuum seal before referred to.

Air to support combustion at the burner is admitted via the holes 11a in the cover plate 11, and the housing 12, to the combustion area 14, and provision can be made by means of a shutter acting in relation to the holes 11a in the cover plate 11, if desired.

It is desirable that a filter 19 be inserted in the fuel line 4a, between the tank 1 and the regulator 16.

In order to operate the burner, a small quantity of methylated spirit or other volatile fuel is placed in the cup or depression 15, in the housing 12, by any convenient means, and ignited, a door being provided in the side of the housing 12, in the apparatus illustrated in Figure 2, to enable this to be done, following which the fuel control cock 7 is opened to the full extent, which operation also opens the air admission holes 11a.

The regulator 16 is set to the setting which will permit only the maximum heat required, to be generated.

Fuel now flows via the line 4 and vaporizer tube 5 into the expansion chamber 2, until it reaches the level covering the lower end of the pressure take off tube 8, whereupon the vacuum seal is set up in the tank 1, and fuel ceases to flow from the same.

Under the action of heat from the burning of the preheating fuel in the cup or depression 15, the fuel in the chamber 2 is vaporized and converted into gas under pressure, some of which passes to the gas nipple jet 3, via the tube 6, and is ignited and assists in further heating the chamber 2.

At the same time gas under pressure passes via the line 9 to the tank 1, and breaks the vacuum seal imposed on the fuel, in the process of priming the burner.

As soon as the vacuum seal is broken, more fuel will be supplied to the vaporizer tube 5 and expansion chamber 2, and consequently more gas will be generated, and the pressure will begin to rise, and as it is impossible for the pressure to rise until gas is being generated freely, no risk of

flaring from the discharge of raw fuel is involved when operating the burner.

The combination of jets is such that more fuel will be delivered than is required to produce the gas to feed the flame, at the burner, therefore there is a constant increase in pressure throughout the system, until the point is reached where the gas being consumed, equals the fuel being delivered.

Control of the fuel is exercised in two ways:

- (1) Automatically, by means of the pressure regulator 16, according to its setting, and,
- (2) Manually, by means of the control cock 7

thereby providing for complete and positive control of the burner at all times.

Although the burner operates satisfactorily, on low heads of fuel, it is susceptible to changes of fuel level, when operating on low heads, which necessitates periodic adjustment of the fuel control cock 7, to keep the operating pressure steady, the use of the pressure regulator 16, and suitable elevation of the tank 1, however, giving a continued steadier performance and avoiding the necessity for such adjustment. This particularly applies if the tank 1 is mounted with its longitudinal axis horizontal, as opposed to vertical.

What I do claim and desire to obtain by Letters Patent of the United States of America is:

30 1. An oil burner and fuel feeding system for same comprising a fuel tank, a circuit comprised in part by a fuel line extending from the tank, a heat interchange device through which the fuel line passes and an expansion chamber into which the fuel line leads, and said circuit including also a back pressure line extending from the expansion chamber through the heat interchange device to the fuel tank above the fuel level therein.

40 2. An oil burner and fuel feeding system as recited in claim 1 in which the fuel line intermediate the fuel tank and the burner includes pressure regulating means operated by the differential between the gravity flow in the fuel line and the back pressure in the back pressure line.

45 3. An oil burner and fuel feeding system as recited in claim 1 in which the circuit includes a vaporizer tube projecting into the expansion chamber and to which the fuel line is connected and a pressure take off tube extending from the expansion chamber to which the back pressure line is connected.

50 4. An oil burner and fuel feeding system as recited in claim 1 in which the expansion chamber is provided with a gas nipple jet connected thereto by a tube which tube conducts gas to the gas nipple jet from the expansion chamber and the gas nipple jet and tube conducts air to the expansion chamber and the back pressure line when the burner is not operating.

55 5. An oil burner and fuel feeding system as recited in claim 1 in which the back pressure line is connected to the expansion chamber by a pressure take off tube extending adjacent the bottom of the expansion chamber whereby its inner end will be closed by liquid fuel collecting in the expansion chamber for the purpose of enabling a vacuum seal to be established in the fuel tank.

60 6. An oil burner and fuel feeding system as recited in claim 1 in which the fuel line intermediate the fuel tank and the burner includes pressure regulating means operated by the differential between the gravity flow in the fuel line and the back pressure in the back pressure line, a vaporizer tube extending into the expansion chamber and a limiting jet intermediate the

pressure regulating means and the vaporizer tube.

7. An oil burner and fuel feeding system as recited in claim 1 in which the fuel line intermediate the fuel tank and the burner includes pressure regulating means operated by the differential between the gravity flow in the fuel line and the back pressure in the back pressure line, a vaporizer tube extending into the expansion chamber, a manually operated valve intermediate the pressure regulating means and the vaporizer tube, and a limiting jet intermediate the manually operated valve and the vaporizer tube.

8. An oil burner and fuel feeding system is recited in claim 1 in which the back pressure line is connected to the expansion chamber by a pressure take off tube and a reducing jet is incorporated in the back pressure line adjacent the pressure take off tube for effecting a reduction in temperature of the gas which passes through the back pressure line.

9. An oil burner and fuel feed system for the same comprising, a cover plate having air admission holes therein cooperable with a furnace or fire box or the like, a housing extending from the cover plate and adapted for insertion in the furnace or fire box, a fuel tank supported by said plate, said housing having an expansion chamber therein, an inverted combustion cone mounted in spaced relation to the expansion chamber to provide a combustion area between the expansion chamber and the cone, a fuel line
